UNITED STATES PATENT OFFICE.

JAMES BALL, OF HOLYOKE, MASSACHUSETTS, ASSIGNOR TO THE HOLYOKE ENVELOPE COMPANY, OF SAME PLACE.

MACHINE FOR MAKING AND PRINTING ENVELOPES.

SPECIFICATION forming part of Letters Patent No. 449,894, dated April 7, 1891.

Application filed November 10, 1890. Serial No. 370,895. (No model.)

To all whom it may concern:

Be it known that I, JAMES BALL, a citizen of the United States, residing at Holyoke, in the county of Hampden and State of Massachusetts, have invented new and useful Improvements in Machines for Making and Printing Envelopes, of which the following is a specification.

This invention relates to improvements in machines for making and imprinting envelopes, the object of the invention being to improve the construction of envelope-machines, whereby they are rendered of unusual practicability to the end of certain and rapid

operation.

As a preliminary to the detailed description to be hereinafter given, the nature of the invention may be more easily and clearly understood by briefly setting forth the successive operation of the parts upon a blank to form the same into an envelope. The blanks are supplied, as usual, by a novel arrangement of pneumatic sucker or picker fingers. The blank is then conveyed rearwardly a suitable distance and is momentarily held stationary, the printing devices then acting to print the blank upon the under side thereof. The blank is then conveyed rearwardly still farther a suitable distance, and again held stationary for an instant, it then being subjected at the flaps thereof to the gumming action of the gummers, and the blank is then further conveyed to the suitable position over the creasing-plunger, which also carries it downward onto the folding-bed. The blank being then folded by the folding-wings is discharged into the drying-chain and finally disposed of in any usual or approved manner, and under the construction and arrangement

of parts embodied in this machine at one and the same time different blanks are being printed, gummed, and folded; and, therefore, to the end of effecting the said operations in an advantageous manner, the invention consists in the constructions and combinations of instrumentalities and parts, all substantially as will hereinafter more fully appear and be particularly set forth in the claims.

Reference is to be had to the accompanying drawings, forming part of this specification,

in which similar characters of reference indicate corresponding parts in all the views.

In the drawings, Figure 1 is a sectional elevation as seen on a plane taken centrally from front to rear of the machine, and indicating, as far as it is possible so to do in a view of this scale, the positions of all the working parts constituting this invention, as well as other parts not particularly novel. Fig. 2 is a plan view of the forward portion of the machine, and Fig. 3 is a front elevation of the upper portion of the machine. These two figures are especially in illustration of the devices for picking up the blanks from the blank-supporting table and of the arrangement relatively thereto of the printing mechanism and ink-supplying devices therefor. Fig. 4 is a plan view of the portion of the machine at the rear of that seen in Fig. 2 and under the creasing-frame, particularly showing the folding mechanism. Fig. 5 is a vertical section taken on the line 5 5, Fig. 4. Fig. 6 is a vertical section of a construction and arrangement of parts taken on the line 6 6 of Figs. 4 and 5, and which will be hereinafter referred to. Fig. 7 is an enlarged view of a folder-wing and a means for adjustably mounting the same, which will be hereinafter more fully described. Fig. 8 is an illustration in perspective of an appliance for operating in conjunction with the platen, and actuated by the presence or non-presence of a blank at the printing place in the machine for blanks. Fig. 9 is an enlarged perspective view illustrative of a portion of the ink supplying and distributing devices for the printing mechanism.

In the drawings, A represents the table of the machine, of which latter a indicates what is termed the "front," and b the "rear." 90

The machine is primarily driven through the shaft 1, and there are provided for the accommodation of the numerous cams necessary for the various movements shafts 2, 3, 4, and 5, which receive their properly-speeded 95 rotary motions through suitable gearing.

c indicates the blank-elevating table, which is shown as supported on a yoke 10 and automatically receives its gradual upward movement to maintain the top of the constantly- 100

lowering pile *d* of blanks within the reach of the pickers by means of mechanism which is but partially shown, and which will not be herein described, as constituting no part of the present invention. The supporting-yoke 10 for the blank-elevating table is provided with a couple of vertical posts 12 12, rigidly affixed thereto, which play through guide-tubes 13 13, fixed to the table A, and by this means the elevating mechanism is steadily moved and guided. The pickers are of the suction class, and the same and the actuating mechanism therefor, together with the separating devices, are shown in Figs. 1, 2, and 3 of the drawings, and will now be particularly described. Three picker-tubes 14 14 and 15 are provided, one for taking on and lifting at each end flap of the blank and one for the rear flap. The pair 14 14 for lifting the ends of the blank are carried in unison on the forward ends of radial arms 16 16 of the horizontal and suitably-mounted rock-shaft 17, which is rocked by means of the connecting-rod 18, engaging the radial arm 19 of said rock-shaft, the lower end of said rod having an engagement with a cam 20 on shaft 5. As the shaft 5 is geared down for a slower rotation than the other cam-carrying shafts of the machine, the cam 20 has circumferentially double sets of working-surfaces, whereby on one rotation of said shaft there will be two rising-and-falling movements imparted to the said end suction-pickers. The picker-tube 15 is independently mounted and moved, being carried on a support 22, which is in the form of a radial arm adjustably fixed on a rod or bar 24, which is carried by a pair of arms 25, radially mounted on rocking journals 26, that have suitable bearings in the brackets 27 27. One of said journals is provided with an arm 28, to which the connecting-rod 29 has an engagement, the other end of said rod having an engagement with a cam 30 on shaft 3. The suction is secured in said picker-tubes through their connection with suitable suction-pumps by means of the flexible pipe-connections 32 had between the tubes and the pumps, respectively, therefor.

The two suction-pumps 33 33 for the pickers 14 14 are mounted on a frame 34, pivotally hung on one of the immovable supports of the machine and adapted to have a swinging movement under the action of the reciprocating piston-rods 35 35 playing therein and which receive their motions from their connection with the radial arm 36 of a lever, another arm 38 of which lever is in engagement with and is moved by a cam 37 on shaft 3. An easy movement of the pistons and not one liable to any crippling effect is insured by the lever 39, intermediately pivoted on the end of the arm 36, and to the extremities of which lever the pump-piston ends are attached, each arm of said lever serving as a link between one of said arms 36 and the respective piston. The suction for the rear picker is secured therein by the connection

therewith of one of the flexible conduits 32, which is also in communication with a pump 33^a, (indicated by dotted lines in Fig. 1,) having a piston playing therein and actuated by well-known means.

e represent separator-plates adapted for a swinging movement in a horizontal plane and at right angles to the throw of the picker-tubes, and when the said tubes have drawn up the extremities of the blanks said separator-plates are adapted as to suitable portions thereof to be swung under the said extremities and separate them from the remaining blanks of the pile. The said separator-plates are carried on the upper ends of spindles 40 40, which have bearings vertically in tubular posts 42, affixed on the table A, the plane of movement of said plates being just above the proper level for the top of the blank pile. One of the spindles 40 has an arm 43 on its lower end, to which motion is imparted through the connecting-rod 44, the two-armed rock-shaft 45, thrust-rod 46, and cam or eccentric 47 on shaft 4. The swinging motion having been imparted to one of the spindles, as described, the other is caused to swing in unison therewith through the medium of a connecting-rod 48, which is attached to an arm 49 at one side of one of the spindles and to an arm 50, which is projected from the opposite side of the other of the spindles. By this form of connection the separator-plates are caused to simultaneously move toward and away from each other in the same plane.

52 52 represent spring clips or fingers which bear on the edge portions of the blanks, as common in envelope-machines. The end pickers are timed to operate in unison to raise the end portions of the blank before the rear flap-picker operates to raise that portion of the blank. There is but slight probability that either of the end pickers will raise portions of two blanks at once; but there is practically no possibility of both pickers raising the opposite end portions of two blanks at once. Therefore, assuming that one end picker lifts the ends of two blanks, while the other end picker lifts the ends of one blank, one separator-plate is swung under the end flaps of two blanks, while the opposite plate is under the end flap of but a single blank. (See Fig. 3.) The rear flap-suction picker then operating will only raise the rear portion of the one blank, for the right-hand separator, lying over the second blank, holds such blank from being lifted by the rear picker, and the draft by the latter being centrally related as to both end flaps will only raise the rear half or other desired proportion of the uppermost blank. The fact that while two or more blanks may at one end of the pile lie above the separator-plate thereat the uppermost blank by its other end is separated from the remainder of the pile, overcomes any suction which may exist between the top blank and the one next below, and therefore any liability of the rear

picker taking up more than one blank is reduced to a minimum. The rear portion of the uppermost blank having been separated, as above described, the blank is then taken by the blank-carriage *f* and conveyed to the position for receiving the imprint from the printing mechanism, the position of which is plainly shown in Fig. 1 under the arch-standard 53 and by the dotted lines *z* in Fig. 2. The blank-carriage *f* has its reciprocating movements through a course from front to rear of the machine about equal in length to the distance between the middle of the pile *d* of blanks to the middle of the type-bed *h*. The blank having been brought to its position for printing is supported and confined on the forwardly-extended part of a suitable horizontal supporting part—such, for instance, as the creasing-frame 54, which constitutes the support and slideway for said blank-carriage *f*. In the printing operation the type-bed moves upwardly and the platen *g* moves downwardly to meet same. The upward throw of the type-bed *h* is imparted through the working of cam and toggle mechanism, as common in printing-machines, and the movements of the platen are insured through the operation of mechanism which it is believed embodies some features of novelty to be now set forth.

55 represents a rock-shaft ranging across the machine and along under the arch-standard 53 and provided with a radial arm 56, to the extremity of which the thrust-rod 57, actuated by cam 58 on shaft 3, has a pin-and-slot engagement, the spring 59 serving to usually maintain a pin 61 of the radial arm 56 at or near the bottom of the slot 60, which is in the upper end of the said thrust-rod 57, and except at such times as unusual resistance is present against the downward projection of the platen.

62 represents one member of the platen-operating toggle and is rigidly affixed to the shaft 55, and 63 is the other toggle member, pivotally connected to an upper portion of the platen. The platen is constrained to its proper vertical movement by means of the Z-shaped link-arms 65, which are by their forward ends pivotally connected to the said platen in axial coincidence with the pivoting thereto of the toggle member 63, the rear extremities of said arms 65 being pivotally hung, as at 66, to a suitable fixed part of the machine. The downward thrust of the rod 57 causes the straightening of the toggle and the downward projection of the platen, the arms 65 at that time having a downwardly-swinging movement, and the spring 59 at such time serving to constitute, in substance, a medium for fixed relations between the thrust-rod 57, which has a positive movement, and the rocker-shaft arm 56. At the time the platen has been brought to impact against the blank and the type-bed thereunder further straightening of the toggle of course ceases, and whatever throw the thrust-rod 57 must have under the forcing

action of its cam is provided for without further forcing action on the platen by the then yielding of the spring, the slotted portion of 70 the thrust-rod moving downwardly over the pin on the arm 56.

A device is provided to act on the rear of the blank when it is brought to its position for being printed, and consists of a finger 70, 75 formed on the rocking rod 72, which receives its rocking motion through the connection with the arm 73 thereof of the thrust-rod 74, which is given its reciprocatory motion by a cam not shown, but which is provided on shaft 80 4, and acts in the same manner as does the cam 58 upon the rod 57 and as other of the cams shown act upon other of the thrust-rods. Immediately the blank is brought forward to its printing position the said last-described 85 mechanism operates to press the finger upon the middle edge portion of the rear flap thereof, holding it upon the frame-extension 54, said hold thereof continuing until after the printing-bed has separated from the platen. 90

Novel mechanism is provided for inking the type on the type-bed at the time the latter is in its lowermost position, which I will now proceed to describe. The same may be briefly stated to consist of an ink fountain or 95 supply, as at *i*, a roller *j*, for carrying ink from said supply to and upon the border portion of the disk *k*, means for rotating said disk, whereby said inked border portion may be carried into proximity to the border of another 100 rotatable disk *l* in the same horizontal plane, a roller *m*, for distributing the ink which is on the approached border of the disk *k* and spreading it upon the border portion of the disk *l*, and also effecting, after the disk *l* has 105 been turned, the spreading of the ink from said border throughout the entire surface of said disk and also for conveying the ink onto a distributing-roll *o*, which is provided at the rear of the type-bed, and there is another 110 roller *n*, mounted for a forwardly and rearwardly reciprocating movement and for taking ink from the said distributing-roll *o* and inking the type, and for also having a contact with still another distributing-roll *p*, which is 115 forward of the type-bed. The plane of the top surface of the disks *k* and *l* and of the distributing-rolls *o* and *p* is coincident with the top of the type-bed when the same is in its lowered position. 120

The individual instrumentalities comprised in the inking mechanism just outlined will be now described more in detail.

The ink-supply *i* consists of an ink-well 125 162, which is supported in a position some- what above the top of the table *A*, and, in fact, above the top of the disks *k* and *l*, and said ink-receptacle has a roller 163 therein, the lower peripheral portion of which extends through an aperture in the bottom of said 130 receptacle, and with the borders of which aperture the said roller has a close fit. The roller is given an intermittent rotary motion through means well known in this class of

ink-supply devices. The ink-carrying roller *j* is mounted on a suitable arbor, the extremities 64 of which slide on horizontal guide-rods 165 165, suitably supported and extended at right angles to the line of travel of the envelope-blank. The reciprocatory movement of the said roller *j*, whereby it is caused to have a contact by its upper side with the roller 163 of the ink-receptacle, and then by its under side to run upon the disk *k*, is imparted by the connection with its arbor of the links 166 166, which also have a connection with the radial arms 67 67 of the rock-shaft 68, there being on said rock-shaft a radial arm 69, to which one end of a connecting-rod 80 is attached, the other end thereof being connected to an intermediately-pivoted lever 82, which lever receives its reciprocatory movement by a cam 83 on one of the cam-carrying shafts.

The disks *k* and *l* have toothed borders, as clearly shown in the drawings, which mesh as gear-wheels, the one *k* being positively driven by the pallet 84, which is carried on an arm 85, hung for its center of swinging movement upon the axial post 86 of disk *k*, and receives its swinging motion by means of the link 87, connected to said rod 85 and to one of said radial arms 67, the other disk *l* receiving its slow rotary motion from its mesh with the adjacent disk *k*.

The roller *m*, which is mounted to travel at right angles to the roll *j*, is supported on a rod 88, the ends of which are movable along and guided by fixed horizontal rods 89, and the roll *n* is also mounted on an arbor-rod 90 therefor, the ends of which are also movable on and guided by the said rods 89 89. The arbor-rods 88 and 90 are tied together or form, in substance, one frame-like structure, whereby both of said rolls are moved in unison, and the reciprocatory motion thereof is imparted by means of the link 92, which is connected to the arbor-rod 90 by its one end and by its other to the end of the curved arm 94, affixed to the rock-shaft 95, and which shaft receives its rocking motion from the connection with its arm 96 of the thrust-rod 97, the other end of which being in engagement with the cam 98 on shaft 5.

The roller *m* is adapted to run over the intermeshing portions of the disks *k* and *l*, having an extent of traverse from a position upon the teeth at the rear of the disk *l* and slightly back of the position shown in Fig. 2 therefor to and upon the distributing-roller *o*, and therefore ink which is upon the approached border of the disk *k* will, as the roller *m* runs over such border, distribute it upon the upper surface of the intermeshing teeth of the disk *l*, and then as said toothed portion of disk *l*, which has received the ink in that way, has been brought toward and into the central longitudinal line of the machine coincident with the middle of the blanks and printing-bed the said reciprocating roller will

distribute the ink generally over the surface of the disk *l*, besides conveying same to the distributing-roll *o*. The said distributing-roller *o* and the one *p* are rotated continuously by means of the pulleys 99 and 100 on their arbors and suitably-driven belts. As the roller *m* runs forward, effecting a distribution of ink on the disk *l*, and also conveying ink to the distributing-roll *o*, the roll *n* moves forwardly to ink the type and also to convey ink to said distributing-roll *o*. The latter roll is not absolutely necessary in the ink-supplying devices; but its use is preferred, as an improved inking effect is assured.

The blank-carriage *f*, moving forward under the operation of a well-known form of carriage-operating mechanism, not necessary to be described, after the printing has been effected to take the next blank, and then on its return movement to convey same to the said position for printing, due to the peculiar construction and arrangement of hook-abutments thereof at the time of making its rearward traverse, serves to convey the first blank which has been printed another step rearwardly into a position whereby it may be gummed by the picker *B*, and also due to the peculiar arrangement of other abutment-hooks on said blank-carriage. The blank which has been previously gummed is then caused to be moved another step rearwardly to its proper position over the creasing-frame to be creased by the plunger *C*—that is, the carriage has on the parallel strip-like members *ff* thereof, which play in suitable ways in the said frame 54, as usual in envelope-machines, three sets of hooks *r*, *r*², and *r*³, which are arranged at intervals of separation corresponding to the distance between the middle of the blank pile and the middle of the printing-bed, or between the middle of the latter and the line of the gummer-carrying rod *q*, or between said line and the center of the aperture 102 in the creasing-frame, and all of which mentioned distances are substantially the same, and the extent of movement of said carriage is substantially equal to any one of said distances. The operation of the said blank-carrier may be perhaps as well understood if it is assumed that the machine is just being started up with the said carriage in its rearmost position ready to be projected forward, and so as said carriage is moved forwardly to its limit the forward hooks *r* thereof are carried just in advance of the forward edge of the separated or partially separated blank, and then on the return of the carriage to its rearmost limit the blank is carried to said position for receiving the imprint. On the next forward movement of the carriage the second set of abutment-hooks *r*² thereof at the time the forward set *r* is engaging another blank at the pile, is projected just in advance of said first and then printed blank, and then as the carriage moves rearwardly to bring the second blank to position for its imprint the first-

named blank is conveyed to the position for its being gummed, and again as the carriage for the third time moves forward to engage a third blank at the pile the rear set of abutment-hooks ⁷³ engage the said first-named and then gummed blank and convey the same to its proper position over the creasing-frame while the second blank is being brought to its position to be gummed, the third blank ⁷⁰ then coming to the position to be printed, and so it will be seen that during the regular running of the machine there will be three blanks on the carriage to be moved step by step between the successive operations respectively ⁷⁵ had thereon.

I have devised as a part of the present invention improved devices for preventing the impact between the platen and the type-bed on the failure from any cause of an envelope-blank to be brought to the printing position, and said device embodies electrical appliances which are controlled by the presence or non-presence of a blank at the printing position, and which electrical appliances in turn control the extent of rock of the said rock-shaft 55. Upon said rock-shaft I affix a radial arm 110, which under normal conditions has a swinging motion adjacent to but not to be intercepted by a hooked extremity ⁸⁰ of a lever intermediately pivoted, as at 113, in suitable bearings on the table A, the lower arm 114 of said lever carrying or of itself constituting the armature 115 for an electro-magnet ⁸⁵ s. I also provide on said rock-shaft 55 another radial arm 116, preferably of wood or other material, to constitute an insulator, and upon the extremity of said arm 116 is supported a feeler-finger or rod 118. As said shaft 55 is rocked to downwardly project the ⁹⁰ platen the said feeler 118 is also downwardly carried, so that it will bear upon the blank over the carriage and said support 54, if the blank is present thereon, and over the printing-bed, or, if absent therefrom, the end of ⁹⁵ said feeler will bear upon the said carriage or on the said support 54 of the gum-box frame. From the said carriage f or part 54, whichever is to constitute the contact-piece, an electric conductor 120 runs to the said ¹⁰⁰ electro-magnet, and from the latter another electric conductor runs to a connection with the said feeler, and there is comprised in one of said electric conductors, as usual for electric circuits, a battery or other form of generator 123. The said feeler 118, instead of being a spring-finger, as it might be, is spring-supported with relation to said insulated arm 116, so as to have a yielding upward movement with relation to its carrying-arm. So it ¹⁰⁵ will be seen that each time the shaft 55 rocks and the feeler 118 is downwardly moved upon the blank, then properly thereunder, due to the said blank acting as an insulation between the feeler 118, to which wire 122 is connected, and the contact part thereunder, to which wire 120 is connected, there will be

no actuation of the electrical devices; but on the failure of a blank to properly come under the platen, the said feeler moving down in advance of the platen on making a contact ¹¹⁰ establishes a circuit, and the attraction by the electro-magnet of the armature swings the hooked extension thereof to intercept the radial arm 110 in its swing and prevents the platen from being carried to an impact with the type, and at this time the thrust-rod in making its complete downward stroke runs by its slotted portion over the pin of arm 56, the spring 59 at such time being elongated, ¹¹⁵ as is plain.

In this machine I employ a bottom for the folding devices, which consists of a series of metallic sections ¹²⁰ t, hinged to each other to form an endless band, and supporting-blocks ¹²⁵ u u', upon which said section-formed band is mounted, said blocks being supported on shafts v and v'. The shaft v is mounted in fixed bearings, while the shaft v' has bearings in a horizontal yoke-bar 125, (which for purposes of rigidity and even carrying of the ¹³⁰ mechanism may be duplicated,) and the said yoke-bar by its one end is pivotally mounted on or axially coincident with the shaft v and is given an intermittent swinging motion in a vertical plane through means of the cam ¹³⁵ 126 on shaft 3 and the rod 127. This endless band is disposed within an aperture of the table and has a step-by-step movement at the time the yoke-bar 125 and the forward supporting-block u' are lowered, so that after ¹⁴⁰ 100 each envelope-blank has been folded and discharged and before a new blank is brought to the action of the folder another section t will be brought upon the upper side of the forward block u' to form the fresh folding bottom. When the yoke-bar 125 is downwardly ¹⁴⁵ swung, the forward movement of the section-formed band is given by the rotation of the carrying-blocks u u' by means of the pallet-and-ratchet device shown on the shaft of said ¹⁵⁰ 110 block u at the right hand of Fig. 1 and actuated from the cam 130 and the connections 131 between same and the said pallet, the rotation of the other block being consequent upon the movement of the sections so ¹⁵⁵ secured.

The mechanism constituting the folding bed just above mentioned is more fully and particularly set forth in my application for Letters Patent for improvements in envelope-machines, filed January 21, 1890, Serial No. 337,570; but I have combined therewith and as a part thereof certain details of construction which are of much practical advantage, being especially to the end of insuring, after ¹⁶⁰ 120 the forward carrying-support u' has been turned and as it is raised to its position for properly presenting the top surface of the section t thereon as and for the folding bottom, the rigid and immovable maintenance of ¹⁶⁵ 125 the said block and section thereon in such bed-forming position. The carrying-shaft v' ¹⁷⁰ 130

is therefore extended laterally of the machine under the table A and provided with a block *w* thereon, which is of greater outward extent than and corresponds externally to the 5 block *u'*; but said block *w* has its corner portions abated and forms in the present instance an octagon. The said block *w* is disposed as to its upper portion in a slot 132, which is formed through the table, there being 10 a ledge 133 overhanging said slot. As the shaft *v'*, with the block *u'* thereon, is lowered with the endless band and is turned, the block *w* of course is lowered and turned, and then as the said parts are upwardly moved 15 one of the faces of the said block *w* is carried hard against the said overhanging ledge 133, maintaining the shaft and the block *u'* as a part thereof rigid and true.

It will be noticed that the plane at which 20 the blank is folded is a little above the top of the table A, as indicated by the line 135 in Fig. 5, and into which plane the top surface of the endless band is projected when moved to constitute the folding bottom, and it will 25 be noticed that the front and rear flap-folders E and F are hinged to base-pieces 136 136, which at their under sides are cut out, as shown at 137 in Figs. 5 and 6, so as to permit the rising and falling motion of the endless 30 band. Each section of the folding bed has a solid portion under the opening in the creasing-frame, the superficial area thereof being greater than that of the said opening, so that invariably there will be a flat base under 35 every fold of the envelope.

Beneath the endless band a cleansing-roller G is mounted upon the yoke-bars 125 and adapted to bear upon the outer and under surface of whichever band-section *t* is next 40 thereabove. This roll is mounted on an arbor or has gudgeons 140, which are spring-supported on the said yoke-bars 125 and capable of a yielding pressure downwardly under any inequality of the surface of the said 45 band. Beneath the said roller G is a receptacle H for a cleansing liquid or solution, having an open top, and into which liquid the said roll will, by its lower peripheral portion, be entered at each depression of the endless 50 band mechanism. Said cleansing-roll is rotated for its wiping action upon the sections *t*, due to the frictional contact with and the traveling movement of the latter. The end flap-folders J (but one of which is positively 55 shown in Fig. 4) are hinged to base-pieces 141, which are carried on the extremities of spring-arms 142, which arms by their other extremities are bolted to the table. One or more screw-studs 145 are passed with a screw en- 60 gagement vertically through each base-piece 141 and by their lower ends bear upon the table, and by properly turning said screw-studs the said base-pieces may be vertically adjusted with the utmost nicety, whereby the 65 end-flap-folding wings may most advantageously be operated in conjunction with the

bottom formed by one of the sections of the said endless band.

Having fully described my invention, what I claim, and desire to secure by Letters Patent, is—

1. In an envelope-machine, the combination, with the blank-supporting table, of a pair of reciprocatory suction-pickers operating over the ends of said table to lift the 75 ends of blanks, separators adapted to be moved between the lifted end portions of the uppermost blank and the blanks below the same, means for moving said separators, a reciprocatory suction-picker operating over 80 the blank and timed to lift one flap thereof after the operation of the said end pickers and separators, and the blank-carriage, substantially as and for the purpose set forth.

2. In an envelope-machine, the combination, with a pair of tubular sucker-pickers, the pumps, and a frame 34, on which same are carried, of pivotally-supported flexible conduits between said pumps and said pickers, the cam-operated lever carrying thereon the 90 double link 39, and the piston-rods of the pumps connected to the extremities of said double link, substantially as and for the purpose set forth.

3. In an envelope-machine, the combination, with the suction-picker 15 and the carrying-arm 22 therefor, of the journal-studs 26 95 26, having the radial arms 25 25, on which is mounted the bar 24, and on which latter the said arm 22 is adjustably secured, and means, 100 substantially as described, for imparting a rocking motion to said journal-studs, for the purpose set forth.

4. In an envelope-machine, the combination, with the separator plates or fingers *ee* 105 and the vertical spindles 40 therefor, mounted in bearings for a rocking motion, one of said spindles provided with a radial arm, of a cam and connections between same and said arm for rocking the latter, radial arms, as the ones 110 49 and 50, on said spindles, and a link 48, connecting said latter-named arms, for the purpose set forth.

5. In a machine for making and printing envelopes, the combination, with the vertically-movable type-bed and the blank-carrier, of the platen above said parts, a rocker-shaft and means for rocking same, a toggle one member of which is carried by said rock-shaft and to the other of which said platen is connected, and link-arms 65, one end of which is pivotally hung on the frame and the other to said platen, substantially as and for the purpose set forth.

6. In a machine for making and printing 125 envelopes, the combination, with the vertically-movable type-bed and the horizontally-movable blank-carrier, of the vertically-movable platen and a rock-shaft carrying one member of a toggle and another member thereof 130 which is secured to the platen, the arm 56 on said shaft, a rotating cam, the rod 57, engag-

- ing same and having its upper end slotted, a pin on said arm which enters said slot, and the spring 59 between said arm and said rod, substantially as and for the purpose set forth.
- 5 7. In a machine for making and printing envelopes, the combination, with a support for an envelope-blank, a rock-shaft having a fixed arm thereon and means for rocking same, and a toggle one member of which is affixed to said rock-shaft and the other to the platen, of an arm on said rock-shaft carrying a feeler, an electro-magnet and the armature therefor constituted by a portion or fixture of an intermediately-pivoted lever, and one arm 15 of which is provided with an engaging portion for said rock-shaft arm, and an electric conductor between the electro-magnet and said feeler and another between the electro-magnet and said envelope-blank support, one of said conductors comprising in its course an electric generator, substantially as and for the purpose set forth.
8. In a machine for making and imprinting envelopes, the combination, with a stationary horizontal supporting part, as the plate 54, 25 the platen and type-bed, both vertically movable in relation to the plane of said plate, and a horizontally-reciprocating envelope-blank carriage, of the rocking rod mounted at the rear of the type-bed and carrying the holding-finger 70 and means for periodically rocking said rod, substantially as and for the purpose set forth.
9. In a machine for making and imprinting envelopes, the combination, with the type-bed, 35 of two disks *k* and *l*, having intermeshing toothed borders and means for rotating said disks, an ink-supply and a roller for taking and conveying ink therefrom to and upon the border of one of said disks, a roller running over the other of said disks and also extended, whereby it may roll over the meshing portions of both thereof, a distributing-roll onto which the said roller *m* runs, and a reciprocating roll *n* for carrying ink from said distributing-roll to the type, substantially as described.
10. In a machine for making and imprinting envelopes, the combination, with the type-bed, 50 of the two disks *k* and *l*, having intermeshing toothed borders and means for rotating said disks, an ink-supply and the reciprocating roller *j* for conveying ink therefrom to and upon the border of the disk *k*, distributing-rolls, one *p* in advance of the type-bed and the other *o* at the rear thereof and between the latter and the said disk *l*, the reciprocating roll *m*, running over the disk *l* and also the intermeshing portion of the other disk and having a traverse to and from the distributing-roll *o*, and the roll *n*, moving in unison with said roll *m* and from said distributing-roll *o* to and from the said distributing-roll *p* and across the type-bed.
- 65 11. In a machine for making and imprint-

ing envelopes, the combination, with the table A, of a printing bed vertically movable through an aperture therein, creasing and folding mechanism at the rear of said printing-bed, the toothed disk *l*, horizontally and 7c rotatably supported on the table intermediate of and in line with the printing-bed and folding mechanism, another disk *k*, having a toothed border which meshes with that of said disk *l*, horizontally and rotatably supported on the table in a line at right angles to said common line of the type-bed and folding mechanism, and means for rotating said disks, an ink-supply and a roll for conveying ink therefrom to the border of the disk *k*, the 80 roller running over the disk *l* and also over the meshing portions of both disks, and ink carrying and distributing devices for conveying ink from the said disk *l* to the type, substantially as and for the purpose described. 85

12. In an envelope-machine, the combination, with a suitable fixed part of the machine, as the table A, provided with a horizontal ledge or abutment 133, of the movable folding bottom comprising rotating supporting-blocks *u* *u'* and a vertically-movable yoke-bar and means for imparting thereto a rising-and-falling motion, the hinged sections *t* *t*, forming an endless band, mounted on said carrying-blocks, the shaft of the block *u'* being laterally extended and having thereon the block *w* and adapted on the rising of said block *u'* to present the edge of said block *w* into engagement with said ledge 133, for the purpose set forth. 100

13. In an envelope-machine, the combination, with the movable folding bed comprising the endless hinged section-band and end supports therefor, one of which is mounted on a yoke, and means for imparting to said band 105 a forward step-by-step motion and to said yoke a rising-and-falling motion, of a cleansing-roller spring-supported upon said yoke and having a yielding bearing upon the under side of said endless band, and a receptacle for holding a cleansing-liquid, located beneath said roll, and into the liquid in which a portion of said roll is submerged on each depression of said yoke. 110

14. In an envelope-machine, a flap-folder 115 wing and a base-piece to which said wing is hinged, one or more spring-arms by one end suitably confined and supported and by the other carrying said base-piece, and a screw-stud passing with a screw engagement through 120 said base-piece and having by its end thereunder a bearing upon a fixed abutment, as the table, substantially as and for the purpose set forth.

15. In a machine for making and imprinting envelopes, in combination, a blank-supporting table and vertically-reciprocating pneumatic pickers thereabove, printing devices, gumming mechanism, and folding mechanism, all arranged in a common line, and 130

said mechanisms having substantially uniform distances of separation, and a blank-carriage having three sets of abutment-hooks uniformly separated, substantially corresponding to the distance between said mechanisms, and means for imparting thereto a reciprocatory movement substantially corre-

sponding to said distances of separation, substantially as and for the purpose described.
